JOHN W. JEPSON, OF DEPEW, NEW YORK, ASSIGNEE TO GOULD COUPLER COMPANY,
A CORPORATION OF NEW YORK.

ENGINE-STARTING ARRANGEMENT.

1,240,726.

Specification of Letters Patent. Patented Sept. 18, 1917.

Application filed February 25, 1913. Serial No. 450,485.

To all whom it may concern:

Be it known that J. JOHN W. JEPSON, a citizen of the United States, and a resident of Depew, county of Erie and State of New York, have invented certain new and useful Improvements in Engine-Starting Arrangements, of which the following is a specification.

My invention relates to improvements in engine starting arrangements, and one object of the invention is to provide an electrical arrangement for starting internal combustion engines and the like by means of an electric motor of minimum size, yet which will produce the necessary torque at starting, and still be capable of operating at sufficient speed to effectively start the engine in all cases.

Further objects, features and advantages will more clearly appear from the detailed description given below taken in connection with the accompanying sheet of drawings which forms a part of this specification.

In the drawings, Figure 1 is a diagram illustrating my invention in its best form;

Fig. 2 is a diagram illustrating a modification; and

Fig. 3 is a diagram showing the relationship of speed and horsepower in a series motor.

Referring to Fig. 1, 1 represents a four-cylinder gasoline engine having a fly wheel 2 connected to its shaft. The fly wheel 2 is provided with gear teeth 3. 4 represents the armature of a direct current electric motor provided with brushes 5 engaging its commutator 6. The shaft 7 of the motor has slidably mounted thereon, but secured to rotate therewith, a gear 8. The gear 8 carries a collar 9 engaged by a forked lever 10 pivoted at 11. A pivotally mounted operating handle 12 is connected to the lever 10 by a link 13, so that upon throwing the handle 12 the gear 8 may be thrown in or out of mesh with the gear 3. The motor is provided with a series exciting field winding 14, and with a shunt field winding 15. The motor is supplied with direct current from any suitable source, as a storage battery through mains 16 and 17. A switch 18 operated by the lever 10 is adapted to close the motor circuit through the main 17 upon the throwing of the handle 12 to cause the gear 8 to mesh

with the gear 3. 19 represents a resistance adapted to be cut in and out of circuit in series with the shunt field 15 by means of a switch 20. The switch 20 is arranged to be opened by gravity and closed by an electromagnet 21, the operating coil of which is in series in the main 17 on the motor side of the switch 18.

In operation, when it is desired to start the engine 1 the hand lever 12 is thrown to place the gear 8 in mesh with the gear 3, and thus mechanically connect the motor so that it may drive the fly wheel and start the engine. This action also closes the switch 8, thereby causing the motor to be energized. Immediately a heavy current passes through the motor, causing the same to produce sufficient torque to start the engine. This current passing through the electromagnet 21 causes the switch 20 to be raised thereby, whereby the resistance 19 is shunted and the shunt field 15 is energized to its full extent to aid the series field 14.

As the motor speeds up, subject to the well known laws governing the operation of series and compound motors, the current in the armature and series field falls off until a point is reached where a further increase in speed means a decrease in horsepower, as illustrated in Fig. 3. It will be understood by those familiar with the characteristics of such motors, that if the field of the motor be now weakened, it will be capable of running at an increased speed without any material decrease in horsepower. Accordingly, when the motor has reached this critical predetermined condition as evidenced by the decrease in current to a predetermined value, the magnet 21 becomes so weakened that the switch 20 opens, thus throwing the resistance 19 in series with the field 15 to decrease the current in the shunt exciting winding, and materially weakening the field excitation of the motor. This permits the motor to run at an abnormal speed so that it will drive the engine at the necessary speed for effective starting.

In prior arrangements for starting internal combustion engines employing an electric motor great trouble has been experienced in that if the motor was designed to run at the high speed necessary for the effective starting under the many various

conditions (especially with the gas engines of motor vehicles) the motor either would not produce the necessary starting torque or else was necessarily of such large size that its use on motor vehicles was practically prohibitive. By my improved arrangement, however, a small motor is wound to normally produce the necessary field strength for starting, and then when the maximum full load speed is reached the field of the motor is automatically weakened to permit of an abnormal increase in speed of the motor when it has reached the predetermined electrical condition desired.

15 The arrangement shown in Fig. 2 is the same as that shown in Fig. 1 except that the resistance 19 and shunt field 15 are omitted and the switch 20 is made to cause the weakening of the field of the motor at the proper time by shunting out a portion of the windings of the series field. Obviously, many other ways will suggest themselves to those skilled in the art for automatically increasing the speed of the motor at the desired point, and although I have described my improvements in great detail and with respect to certain embodiments thereof, nevertheless, I do not desire to be limited to such details except as clearly pointed out in the appended claims since many changes and modifications may well be made without departing from the spirit and scope of my invention in its broader aspects.

35 Having fully and clearly described my invention, what I claim as new and desire to secure by Letters Patent, is:

1. In an arrangement of the character described, the combination of an internal combustion engine having a fly wheel, an electric motor adapted to be thrown into mechanical connection with the engine to start the engine and drive the fly wheel, said motor being provided with field producing means including a series exciting field winding, and means for automatically weakening the field of the motor when the armature current of the motor has decreased to a predetermined value.
- 50 2. In an arrangement of the character described, the combination of an internal combustion engine having a fly wheel, an electric motor adapted to be thrown into mechanical connection with the engine to start the engine and drive the fly wheel, said motor being provided with field producing means including a series exciting field winding, and means for automatically weakening the field of the motor to permit of an abnormal increase in speed thereof when the load on the motor has decreased to a predetermined value.
- 65 3. In an arrangement of the character described, the combination of an internal combustion engine having a fly wheel, an

electric motor mechanically connected with the engine and provided with field producing means including series and shunt exciting field windings and means for automatically weakening the field of the motor to permit of an abnormal increase in speed thereof with the motor still energized by the series field winding and responsive to a decrease in load on the motor.

4. In an arrangement of the character described, the combination of an internal combustion engine, a motor for starting said engine having field producing means including a series exciting field winding and means for automatically weakening the field of the motor to permit of an abnormal increase in speed thereof after the motor has reached a predetermined condition with the motor still energized by the series field winding and responsive to a decrease in load on the motor.

5. In an arrangement of the character described, the combination of an internal combustion engine, a dynamo electric machine mechanically connected to the engine to start the same, said dynamo electric machine being provided with field producing means including a series exciting field winding, and means for automatically weakening the field of the machine to permit of abnormal increase in speed thereof after the machine has reached a predetermined condition.

6. In an arrangement of the character described, the combination of an internal combustion engine, a dynamo electric machine mechanically connected to the engine to start the same, said dynamo electric machine being provided with field producing means including a series exciting field winding and a shunt field winding and means for automatically weakening the field of the machine to permit of an abnormal increase in speed thereof as the load on the machine decreases.

7. In an arrangement of the character described, the combination of an internal combustion engine, a dynamo electric machine mechanically connected to the engine to start the same, and means for automatically permitting an abnormal increase in speed of the machine responsive to a decrease in load on the machine.

8. In an arrangement of the character described, the combination of an internal combustion engine having a fly wheel, an electric motor adapted to be thrown into mechanical connection with the engine to start the engine and drive the fly wheel, said motor being provided with field producing means including a series exciting field winding and a shunt exciting field winding, and means for automatically weakening the field of the motor when the armature current of the motor has de-

creased to a predetermined value, said means embracing means for decreasing the current in the shunt winding.

9. In an arrangement of the character described, the combination of an internal combustion engine, an electric motor mechanically connected to the engine to start the same, and means for automatically weakening the field of the motor to permit of an abnormal increase in speed thereof as the engine assumes to drive itself.

10. In an arrangement of the character described, the combination of an internal combustion engine having a fly wheel, an electric motor adapted to be thrown into mechanical connection with the engine to start the engine and drive the fly wheel, said motor being provided with field producing means including a series exciting field winding, and a shunt exciting field winding, and means for automatically weakening the field of the motor when the armature current of the motor has decreased to a predetermined value, said means embracing means for decreasing the current in said shunt winding when the current in the series winding decreases to a predetermined value.

11. In an arrangement of the character described, the combination of an internal combustion engine, a dynamo electric machine mechanically connected to the engine to start the same, said dynamo electric machine being provided with field producing means including a series exciting field winding, and means for automatically weakening the field of the machine to permit of an abnormal increase in speed thereof, responsive to a decrease in current through the motor.

12. In an arrangement of the character described, the combination of an internal combustion engine, a dynamo electric machine mechanically connected to the engine to start the same, said dynamo electric machine being provided with field producing means including a series exciting field winding, and means for automatically weakening the field of the machine to permit of an abnormal increase in speed thereof, responsive to a decrease in current through the motor, with the motor still energized by the series field winding.

13. In an arrangement of the character described, the combination of an internal combustion engine, a dynamo electric machine mechanically connected to the engine to start the same, said dynamo electric machine being provided with field producing means including a series exciting field winding, and means for automatically weaken-

ing the field of the machine to permit of an abnormal increase in speed thereof after the machine has reached a predetermined condition, with the motor still energized by the series field winding.

14. In an arrangement of the character described, the combination of an internal combustion engine having a fly wheel, a motor to start said engine, said motor being provided with field producing means including a series exciting field winding, and means for automatically weakening the field of the motor to permit of an abnormal increase in speed thereof as the load on the motor decreases.

15. In an arrangement of the character described, the combination of an internal combustion engine having a fly wheel, a motor for starting said engine, said motor being provided with field producing means including a series exciting field winding, and means for automatically weakening the field of the motor to permit of an abnormal increase in the speed thereof, with the motor still energized by the series field winding, said means acting responsive to a decrease in current through the motor.

16. In an arrangement of the character described, the combination of an internal combustion engine having a fly wheel, a motor for starting said engine, said motor being provided with field producing means including a series exciting field winding, and a shunt exciting field winding, and means for automatically weakening the field of the motor to permit of an abnormal increase in speed thereof, said means acting responsive to a decrease in current through the motor.

17. In an arrangement of the character described, the combination of an internal combustion engine, an electric motor, means for connecting the motor to the engine to start the latter, and means for automatically weakening the motor field as the load on the motor decreases to increase the speed thereof.

18. In an arrangement of the character described, the combination of an internal combustion engine, a starting motor therefor, and means for automatically weakening the motor field as the load on the motor decreases to increase the speed thereof.

In testimony whereof, I have signed my name to this specification, in the presence of two subscribing witnesses.

JOHN W. JEPSON.
